UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,481, dated September 20, 1881.

Application filed August 9, 1881. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a group composed of four rosettes on a stem, *a*, which has leaves, flowers, and buds.

The stem *a* seems to grow out of the group B, 15 of three rosettes, that are also surrounded by leaves. A stem, *b*, grows out of group B, and carries first a small cluster, C, of rosettes, and then a larger cluster, D, of rosettes, near which is a peculiar leaf-like figure, E. Near the figure E is another cluster, F, of rosettes.

I claim—

The design for carpets, consisting of the figures A B C D E F *a* *b*, substantially as shown.

HENRY HUNT.
